CIGAR PACKAGE

Morris S. Kayner, New York, N. Y.

Application November 10, 1933, Serial No. 697,486

16 Claims. (Cl. 206—44)

The herein described invention relates to packages for tobacco and the like, and is primarily intended as a cigar package of pocket size.

It is especially designed for men who purchase more than one cigar at a time but not the regular size box containing twenty-five or fifty.

Among the objects of the invention are to provide a package of a convenient size for carrying in the breast pocket of a coat or vest.

Another object is to provide means for retaining the individual cigars in an upright position in the package, to prevent their falling over, breaking, or bending, and at the same time, to facilitate removal of an individual cigar.

Still another object contemplates the provision of a package in which the individual cigars may be adequately displayed without disturbing the package or seals, whereby the quality, brand, style, etc. may be readily determined before purchase.

The present invention presents a novel solution of the problem of sealing the end of a package with the internal revenue stamp required by law, in such a manner that no cigars can be removed without breaking the seal, while at the same time permitting a display of the ends of the cigars.

To the attainment of the foregoing and other objects which will appear as the description proceeds, reference may be made to the accompanying sheet of drawing, in which:

Fig. 1 represents a perspective view of a preferred form of package.

Fig. 2 represents a vertical section partly in elevation thereof.

Fig. 3 is a section on the line 3—3 of Fig. 2.

Fig. 4 is a perspective disassembled view showing details of the seal and cover of Fig. 1.

Fig. 5 is a view similar to Fig. 2 but illustrating a slightly modified form of package, and

Fig. 6 is a perspective view similar to Fig. 4 but illustrating the modification of Fig. 5.

Referring more specifically to the drawing in which like reference numerals designate like parts, it will be observed that the package consists of a skeleton framework formed from any suitably designed blank (it is contemplated that this package may be made from blanks of various configuration, the only essential being that the finished package be as herein described and claimed) and comprises a top elliptical strap 10, a bottom elliptical strap 12, the straps 10 and 12 being connected and spaced from each other by longitudinally extending struts 14 and 16. The lower band or strap 12 will be closed by a bottom wall 18 which may be formed integral with the element 12, or may be secured thereto by a paper covering 20, as desired. Such paper coverings are frequently used for advertising purposes, and the like, and form a convenient means of holding

the several parts of the blank in assembled and

shaped relation. Advantage may be taken of this fact to conceal the joint or seam line 22 produced by bringing the edges of the blank into adjacent relationship if a blank of such type is used.

Inasmuch as most cigars are marketed at the present time in individual Cellophane wrappers, it is contemplated that the skeleton framework will be complete without the addition of any further material, but it will be obvious that the package may be provided with a Cellophane wrapper or liner, if thought necessary.

From the structure thus far described, it will be evident that a plurality of cigars, five being a convenient number for pocket purposes, may be placed within the framework to complete the package.

Assuming that one or more cigars is removed from the package, there would ordinarily be a tendency in the remaining cigars to fall sideways into the vacated space and this is objectionable because of danger of breakage of the unused cigars. In order to avoid this objection, it is contemplated that the cigars be separated or partitioned from each other by a retaining means

effective to hold each individual cigar in its original upright position. Expense of manufacture, coupled with the fact that the package comprises a framework without side walls of material area, offer a problem, and the present invention offers

a unique solution thereof. An elastic 24 is reeved through the opposed walls of the upper strap 10, transversely of the package, as shown clearly in Fig. 3. This is accomplished by securing one end of the elastic at 26, running it across and

through the opposite wall, traversing the external face of said wall for a distance equal to the diameter of a cigar, returning the elastic to the first wall and continuing the procedure until the end is brought out at the point 28. The

ends may be secured in any convenient manner as by knotting, or gluing same to the member 10. A preferred form of securing the ends would be by means of an outer covering or wrapper, such as 20, which could be utilized readily to finish

off and complete the package, and which being pasted to the framework would readily serve to secure the elastic in place. It is intended that the foregoing suggestions for securing the elastic be illustrative only, and not limiting as various other means of securing such elastic might be utilized.

The ends 26 and 28 could be brought together and vulcanized, or an endless band might be used in the first instance by forming vertical

slits in the member 10 from the top edge thereof downwardly, and band inserted in these slits, rather than utilizing a straight band reeved back and forth.

Obviously, any equivalent of elastic might be

used. In fact, a non-elastic string might serve the purpose, but elastic is preferred as it can be positioned in a slightly tensioned condition and will thus serve to more adequately secure 5 the cigars in position, without, however, offering resistance to removal thereof.

In Figs. 1, 2 and 4, there is illustrated a form 10 of cigar having a built-in mouth piece. The internal revenue law requires that packages of 15 cigars be sealed in such a manner as to prevent removal of a single unit without destroying a seal in the nature of an internal revenue stamp. In order to insure that these conditions be fully met, there is provided a light strip 30, which may 20 be of relatively stiff material such as wood or fibre, such strip being placed over the mouth piece ends of the cigars and secured in position by the usual internal revenue stamp 32. If, for 25 any reason, the cigars are sold other than in unit packages and a single stamp used on a car- 30 ton of say one hundred units, any suitable ad- 35 vertising or trade-mark label may be used in lieu of the internal revenue stamp. The material of the member 30 being stiff, it will be impossible 40 to bend an end thereof for the purpose of remov- 45 ing a single cigar, thus insuring retention of the cigars until the stamp 32 is broken. Use of the member 30 requires a fairly substantial surface, 50 such as the mouth pieces of the cigars, upon 55 which the member may rest. Accordingly, when 60 this package is used for cigars which do not have a mouth piece or a flat butt end, some other means must be provided to close and seal the package and, accordingly, there is illustrated in 65 Figs. 5 and 6 a type of cover which is of more 70 general application and which does not rest di- 75 rectly upon the cigars themselves.

This form, while suitable for use with cigars 40 of the type shown in Fig. 1, is very satisfactory 45 with cigars which have a pointed end or which are fragile to an extent insufficient to support a cover. In this form, there is illustrated a cup 50 shaped cover 34 somewhat similar to the bottom 55 12-18 which forms a complete enclosure for the 60 end of the package. The side walls thereof are 65 of a size and shape to rest upon the upper edge 70 of the member 10, encasing the ends of the cigars 75 which may project beyond the member 10. This 80 cover can be sealed readily by means of a stamp 85 32 in a manner similar to that above described.

As an alternative, if the package is made of 55 sufficient length that the cigars do not project 60 beyond the member 10, a flat element such as 65 the member 30 or the top wall 36 of the member 70 34 may be utilized by making such a flat member 75 of a size sufficient to rest upon and engage the 80 edges of the member 10. Closing and sealing the 85 package in the manner described, not only com- 90 plies with Federal and State requirements, but 95 affords adequate display of the ends of the cigars.

The cap and seal, as above described, are pri- 60 marily for purposes wherein unit packages are 65 sold and must be sealed with a revenue stamp to 70 comply with the law. In the event that the cigars 75 are packaged in such a manner that no revenue 80 stamp is necessary for the small package of a few 85 cigars, but can be legally cared for in some other 90 manner, then it will not be necessary to use any 95 seal or sealing device, or any cap such as the 100 members 30 and 34, as the package is otherwise complete for all other practical purposes without them.

As stated above, cigars are usually, individually 105 encased in Cellophane, as indicated at 38. A var- 110 iation from this form would contemplate the pro-

10 vision of a Cellophane bag of sufficient size to accommodate a plurality of cigars, such bag being placed in the skeleton framework, or might include an outer wrapper extending entirely around the framework and secured in position thereto, and it is not intended that this invention shall be limited to any specific form or style of package other than described in the claims appended hereto.

15 This construction is extremely simple, and inexpensive to manufacture, requiring an almost negligible amount of material. The skeleton construction exposes practically all of the contents of the sealed package to inspection by the eye, while the internal construction enhances accessibility to such contents.

Having thus described my invention, what I claim as new and desire to secure by Letters Patent is:—

1. A package for cigars and the like comprising 20 a skeleton framework formed with narrow top and bottom strap members connected to each other by longitudinally extending struts, the lower of said strap members being closed to form a bottom for the package and both of said members 25 being effective to encompass the contents of the package, and a cap of a shape and size substantially commensurate with the area defined by the periphery of said top strap member, said cap being effective to retain the cigars within the package, said top strap member being sub-divided into sections by elastic separators extending internally thereof from side to side of the member. 30

2. A package for cigars and the like having in 35 combination, end sections formed of endless bands of generally elliptical configuration to encompass the cigars in the package, and connected to each other in spaced relation by longitudinally extending struts, and means extending transversely of, and entirely across one of said end sections, to 40 provide separators for the cigars in the package.

3. A package for cigars and the like having in 45 combination, end sections formed of endless bands of generally elliptical configuration to encompass the cigars in the package, and connected to each other in spaced relation by longitudinally extending struts positioned in opposed relation to each other and extending from points intermediate the ends of said sections, and elastic means 50 extending transversely of one of said bands to provide separators for the cigars in the package. 55

4. A package for cigars and the like having in 60 combination, end sections formed of endless bands of generally elliptical configuration to encompass the cigars in the package, and connected to each other in spaced relation by longitudinally extending struts positioned in opposed relation to each other and extending from points intermediate the ends of said sections, and separating means for 65 the cigars in the package comprising an elastic band reeved through one of said bands to provide, transversely extending runs, the transverse runs being arranged in predetermined spaced relation to each other. 70

5. A package for cigars and the like comprising 75 a skeleton framework formed with strap members connected to each other other solely by longitudinally extending struts, the lower of said strap members having a lateral wall forming a bottom for the package, and both of said members 80 being effective to encompass the contents of the package, a cap member of a shape and size substantially commensurate with the area defined by the periphery of said top strap member, effective to retain the contents of the package there- 85 90 95 100 105 110

within, said top strap member being subdivided into sections by separators extending internally thereof from one side to the other of the member.

5 6. A package for cigars and the like having in combination, end sections formed of bands arranged to a general elliptical configuration whereby to encompass the cigars in the package, and connected to each other in spaced relation 10 by longitudinally extending struts positioned in opposed relation to each other and extending from points intermediate the ends of the respective elliptical end sections, and means extending transversely of, and entirely across at least one 15 of said end sections, to provide separators for the cigars in the package.

7. A package for cigars and the like having in combination, end sections formed of bands arranged in generally elliptical configuration to encompass cigars in the package, and connected to each other in spaced relation by longitudinally extending struts positioned in opposed relation to each other and extending from points intermediate the ends of said sections, and separating 25 means for the cigars comprising a cord reeved through one of said bands to provide transversely extending runs, the transverse runs being arranged in predetermined spaced relation to each other.

30 8. As an article of manufacture, a merchandizing package of cigars comprising a receptacle, a plurality of cigars carried therein, with their ends projecting from the mouth thereof, a retaining strip of relatively stiff material for holding the 35 cigars within the receptacle, extending across the ends of the cigars in spaced relation to the mouth of the receptacle, and means for sealing said strip about the cigars to the receptacle.

9. As an article of manufacture, a merchandizing package of cigars comprising a receptacle, a plurality of cigars carried therein, with their ends projecting from the mouth thereof, means in said receptacle for separating the individual cigars from each other effective to hold said cigars in 40 place within the receptacle, a retaining strip of relatively stiff material for holding the cigars within the receptacle, extending across the ends of the cigars in spaced relation to the mouth of the receptacle, and means for sealing said strip about the cigars to the receptacle.

50 10. As an article of manufacture, a merchandizing package of cigars comprising a display receptacle formed with relatively narrow top and bottom strap members, connected to each other by longitudinally extending struts, the lower of said strap members being closed to form a bottom for the package, and the other of said strap members being open to form a mouth for the receptacle, and both of said members being effective to encompass the contents of the package, a plurality of cigars carried in the receptacle with their ends projecting from the mouth thereof, a cap extending across the ends of the cigars in spaced relation to the mouth of the receptacle, and means for sealing said cap to the receptacle.

55 11. As an article of manufacture, a merchandizing package of cigars comprising a display receptacle formed with relatively narrow top and bottom strap members, connected to each other by longitudinally extending struts, the lower of said strap members being closed to form a bottom

for the package, and the other of said strap members being open to form a mouth for the receptacle, and both of said members being effective to encompass the contents of the package, a plurality of cigars carried in the receptacle with their ends projecting from the mouth thereof, means in said receptacle for separating the individual cigars from each other effective to hold said cigars in place within the receptacle, a cap extending across the ends of the cigars in spaced relation to the mouth of the receptacle, and means for sealing said cap to the receptacle.

12. As an article of manufacture, a merchandizing package of cigars comprising a receptacle having a cut-out intermediate its ends for display 15 of contents therein, a plurality of cigars formed with mouth pieces at one end, carried in said receptacle with the mouth pieces projecting from the mouth of the receptacle, a retaining strip of relatively stiff material for holding the cigars 20 within the receptacle positioned upon the ends of the cigar mouth pieces, in spaced relation to the mouth of the receptacle, and means for securing said strip in such position, to the receptacle.

25 13. As an article of manufacture, a merchandizing package of cigars comprising a receptacle having a cut-out intermediate its ends for display of contents therein, a plurality of cigars formed with mouth pieces at one end, carried in said receptacle with the mouth pieces projecting from the mouth of the receptacle, means in said receptacle for separating the individual cigars from each other effective to hold said cigars in place 30 within the receptacle, a retaining strip of relatively stiff material for holding the cigars within the receptacle positioned upon the ends of the cigar mouth pieces, in spaced relation to the mouth of the receptacle, and means for securing said strip in such position, to the receptacle.

35 14. As an article of manufacture, a merchandizing package of cigars comprising a receptacle and a plurality of cigars carried therein, said receptacle being of a length effective to partially expose the cigars beyond the end of the receptacle, 40 means extending across and engageable with the exposed ends of the cigars for holding same within the receptacle, and means for securing said holding means in such position, to the receptacle.

45 15. As an article of manufacture, a merchandizing and display package of cigars, comprising a receptacle, and a plurality of cigars carried therein, said receptacle having a length less than that of the cigars, means extending over and engageable with the exposed, projecting ends of the 50 cigars for holding same within the receptacle, and means for securing said holding means in such position, to the receptacle.

55 16. As an article of manufacture, a merchandizing and display package of cigars, comprising a 60 receptacle, and a plurality of cigars carried therein, means extending transversely back and forth across the interior of said receptacle to separate individual cigars therein from each other, said receptacle having a length less than that of the cigars, means extending over and engageable with the exposed, projecting ends of the cigars for holding same within the receptacle, and means for securing said holding means in such position, to the receptacle.
